HEDDLE FRAME

John Jacob Kaufmann, Elkins Park, Pa., assignor
to Steel Heddle Manufacturing Company,
Philadelphia, Pa., a corporation of Pennsylvania

Application November 12, 1934, Serial No. 752,640

2 Claims. (Cl. 139—91)

This invention relates to heddle frames for looms, and it relates more particularly to the construction and arrangement of such heddle frames.

Heretofore, in that type of heddle frame which

- 5 has been most commonly used for mounting metallic heddles in a loom, spring retaining members have been employed for securing the heddle supporting rods at their ends. These retaining members are usually mounted in the end members 10 of the frame, having portions anchored in said end members at places between the two heddle supporting rods. With this arrangement, certain difficulties are encountered when it is desired to mount certain auxiliary devices in the 15 frame, such for example as the separating wires which are used in connection with the so-called "duplex" type of heddles. Furthermore, the mounting of the heddle rod retaining members in the intermediate portions of the end members 20 precludes the use of guiding devices in connection with the end members, where it is necessary or desirable to prevent side sway of the frames.

Several attempts have heretofore been made to mount the heddle rod retaining members in the 25 frame in such manner as to keep the intermediate portions thereof clear and unobstructed, but none of these has proved entirely satisfactory.

The principal object, therefore, of the present 30 invention is to provide an improved construction of heddle frame in which the heddle rod retaining members are so mounted as to be disposed entirely outside of the space between the heddle rods, whereby the intermediate portions of the 35 end members are left clear and unobstructed over sufficient portions of their outer faces to permit the frames to be guided against side sway, and also to permit the mounting in the end members of various auxiliary devices if desired.

The nature and characteristic features of the 40 invention will be more readily understood from the following description, taken in connection with the accompanying drawing forming part hereof, in which:

Figure 1 is a front elevation of a heddle 45 frame embodying the main features of the present invention;

Fig. 2 is an enlarged fragmentary detail view, partly broken away, of one corner of the frame;

Fig. 3 is an end elevational view of the portion 50 of the frame shown in Fig. 2;

Fig. 4 is a vertical section thereof, taken approximately on the line 4—4 of Fig. 2; and

Fig. 5 is a sectional detail view, taken approximately on the line 5—5 of Fig. 2.

55 It will, of course, be understood that the de-

scription and drawing herein contained are illustrative merely, and that various modifications and changes may be made in the structure disclosed without departing from the spirit of the invention.

Referring to the drawing, in the particular embodiment of the invention therein shown, 10 are the top and bottom rails, which are usually made of wood. The end members 11 are made of strips of flat metal, each of said end members extending across end faces of the rails 10, and being bent over and extending along the outer edges thereof, as at 12. These bent over portions 12 are secured to the rails 10 by wood screws 13. Corner braces 14, of the type shown in my previous Letters Patent No. 980,285, may be employed at the inner end corners of the top and bottom rails, being secured thereto by wood screws 15.

The heddle supporting rods 16 are of the usual type, having their end portions extending through suitable slots in the end members 11. Those portions of each heddle supporting rod which extend outside the end member 11 are provided with apertures 17, for engagement by the retaining members to be hereinafter described.

Any preferred means for supporting the heddle rods 16 intermediate their ends may be employed. As shown in the drawing, the same may comprise an auxiliary rod 18, supported at suitable intervals by screw eyes 19 mounted in the inner edge portion of the rail 10, and having slide hooks 20 mounted thereon which engage said heddle rods.

The heddle rod retaining members, one of which is provided for each end portion of each heddle supporting rod 16, are preferably made of spring wire, and suitably bent, as hereinafter set forth. Each end member 11 has provided, in each of those portions thereof which extend across the end faces of each rail 10, two apertures 21, through which portions of the heddle rod retaining member extend.

From the outermost aperture 21, the end portion 22 of the retaining member extends along the outer face of the end member 11. Another portion 23 of the retaining member extends between the two apertures 21 in the end member 11, and along the inner face thereof. A flexible portion 24 of the retaining member extends inwardly, from the innermost aperture 21 in the end member, toward the end of the heddle supporting rod 16, where it is bent around in hook-like formation, as at 25, extending through the aperture 17 in the extending end portion of the heddle supporting rod 16, which aperture is provided for that purpose.

The end portion of each rail 10 is recessed, as at 26, to permit the portion 23 of the retaining member, which extends along the inner face of the end member 11, to be seated in said recess, so that there will be no interference with the proper mounting of the end member 11 on the end portion of the rail 10.

The present invention is particularly useful in connection with that type of frame in which 10 "duplex" heddles are mounted. These frames are sometimes provided with wires 27 which extend longitudinally in the frame between the two sets of heddles 28, serving to prevent fouling of said heddles on each other. As shown, each end 15 of each of these wires 27 is provided with a loop 29 extending through a suitable aperture in the end member 11, which loop may be engaged by a spring retaining hook 30. The retaining hook 30 may be secured by means of a rivet 31, mounted 20 in the end member 11, as clearly illustrated in the drawing.

It will be noted that, by the arrangement of the heddle rod retaining devices as hereinbefore set forth, the intermediate portion of each end 25 member 11, between the heddle supporting rods 16, is left free of said retaining members, so that 30 the devices for securing the wires 27, or other devices of like character but used for different purposes, may be provided. Where such devices are not used, the end members 11 are left free 35 of obstructions on their outer faces between the heddle supporting rods 16, so that they may be engaged by guide members (not shown) to prevent side sway of the frames, which is frequently desirable. Even in the form shown, 40 where the separator wires 27 are employed, there is still sufficient length of the end members 11 left unobstructed to permit such guide members to be employed if desired.

A heddle frame constructed in accordance with the present invention will also be found to be more rigid, in that a considerable length of the

intermediate portion of each end member is left free of apertures which weaken the same.

I claim:

1. A heddle frame comprising top and bottom rails, end members made of flat strips of metal having portions extending across the end faces of said top and bottom rails, heddle supporting rods having their end portions extending through the end members, and spring wire retaining members mounted in the end members for securing the heddle supporting rods, said retaining members being secured to said end members in the portions thereof which extend across the end faces of the rails, each of said retaining members having a portion extending along the inner face of the end member, and a portion extending inwardly which engages an aperture in the end of the heddle supporting rod, the end portion of the rail having a recess in which is disposed that portion of the retaining member which extends along the inner face of the end member. 5 10 15 20

2. A heddle frame comprising top and bottom rails, end members made of flat strips of metal having portions extending across the end faces of said top and bottom rails, heddle supporting rods having their end portions extending through the end members, and spring wire retaining members mounted in the end members for securing the heddle supporting rods, said end members having apertures in the portions thereof which extend across the end faces of the rails through which apertures portions of the retaining members extend, each of said retaining members also having a portion extending along the outer face of the end member, a portion extending along the inner face of the end member, and a portion extending inwardly having a hook-like terminal which engages an aperture in the end of the heddle supporting rod, the end portion of the rail having a recess in which is disposed that portion of the retaining member which extends along the inner face of the end member. 25 30 35 40

JOHN JACOB KAUFMANN.
